UNITED STATES PATENT OFFICE.

HARRY J. WARTHEN, OF WASHINGTON, DISTRICT OF COLUMBIA.

ELECTRIC SIGNAL FOR RAILWAYS.

1,090,362.

Specification of Letters Patent. Patented Mar. 17, 1914.

Application filed March 24, 1909, Serial No. 485,527. Renewed February 5, 1914. Serial No. 816,842.

To all whom it may concern:

Be it known that I, HARRY J. WARTHEN, a citizen of the United States, residing at Washington, in the District of Columbia, 5 have invented an Electric Signal for Railways, of which the following is a specification.

My invention is an improvement in signal devices for railways, and relates more especially to those devices of this character which are operated by an electric circuit and controlled automatically by a train as it passes over each block or section of track.

The primary object of my present invention is to provide an electric signal system for railways which is operated on a closed circuit in connection with make and break devices, whereby a train passing onto and along the rails of any block or section of the 20 railway will affect the circuit in certain blocks in both directions from the train, in such manner as to establish a signal condition in said blocks, the making and breaking of the circuit controlling the signals being 25 effected automatically.

A further object of my invention is to provide an electric signal system in which the tracks of the railway are included in the circuits, so that the displacement of a rail by a washout or other cause will so affect such circuits as to present a signal condition in the adjoining blocks or sections of the railway.

In the present instance I employ electro-magnets and armatures as the make and break devices, each block or section of track having a pair of electro-magnets which are electrically connected through the rails and when energized serve to electrically connect their armatures, together with supplemental circuits each including a signal rail or conductor, track rails and the connected armatures of certain electro-magnets, whereby such supplemental circuit is either open or closed according to the position of said armatures and condition of the remaining connections; all as hereinafter fully described and set forth in the appended claims.

In the accompanying drawings, which 50 form a part of this specification:—Figure 1 is a diagram, illustrating an application of my invention. Fig. 2 is an enlarged detail view of a pair of electro-magnets and parts which co-act therewith. Fig. 3 is a detail view of a set of armatures.

Like numerals of reference indicate like parts in all the figures of the drawings.

In carrying out my invention the railway is divided into blocks or sections, each provided with a station, and though I have shown in the present instance only five blocks and stations it will be understood, of course, that in practice the number will depend upon the length of the railway and the distance apart the stations are placed. The 60 stations shown in the drawings will be referred to in these specifications as A, B, C, D, and E, respectively, and are so indicated on said drawings.

5 and 6 indicate the track rails, and these 70 are adapted to form the electric conductors for the signaling system, one of these rails, as 5, being disconnected, electrically, at each station by means of an insulating block 7, and also electrically disconnected at a point 75 intermediate the stations by insulating blocks 8, for the purposes hereinafter explained. The other rail, as 6, is continuous and forms a common conductor for both the main and supplemental circuits hereinafter 80 referred to.

At each station are located two electro-magnets or relays, 9 and 10, of conventional form, and in connection with these electro-magnets there are employed armatures 12 85 and 13, respectively, one of said armatures, as 12, having two conducting elements, as 12^a and 12^b, which are insulated from each other (see Fig. 3). Each armature is pivoted at its outer end, as at 14, and when 90 attracted by the magnet is in contact with a conductor-plate 15, common to both, so that the current from a supplemental circuit may pass from one armature to the other. The conductor-plate is provided with contact-points, 16, in the form of set-screws threaded through said plate to form a means of adjustment, as will be obvious. The movement of the armatures away from the magnets is limited by means of suitably insulated stops 17, and as the armatures are pivoted below the magnets they will drop by gravity when said magnets become deenergized, respectively.

The electro-magnets 9 and 10 are energized by batteries 18, which are so placed or connected that the current will have to pass through a length of the track-rails to said magnets, and in the present instance the connections are such that the two relays 105

at adjacent stations and at opposite ends of the same block are connected in a single series circuit. To this end each battery 18 is connected around the insulating joint 8 to the track rail sections 5-5, so that current will pass from one side of the battery through rail section 5, wire 19, to and through relay 9, wire 20, back along rail 6, wire 20 at the other end of the block, relay 10, wire 19, and return along the other section 5 to the other side of the battery, thus maintaining both rails of the track and both relays in a permanently closed series circuit. It will be understood of course that 15 a considerable distance intervenes between stations and that the lengths of the blocks will be determined by the traffic conditions in each particular case. When a train passes along the track it will short circuit the battery 18 from a rail-section 5 to the rail 6, through the wheels of the train, cutting out one of the electro-magnets, according to which rail 5 the train is on; for instance, a train passing to the right from station A 20 on to the rail-section 5 beyond will cut out the electro-magnet 10 of this station, the current then passing from the positive element of the battery to said rail-section 5, through the wheels and axle of the train to track-section 6, along the latter to the wire 20 and into the electro-magnet 9 at station B, from said magnet by wire 19 to the other rail-section 5, and along said rail to the negative element of the battery. When the 25 train passes on to rail-section 5 between said battery and station B it will in like manner cut out magnet 9 of the latter station and restore the energy to magnet 10 of station A. It will be seen, therefore, that a block 30 or section of track which controls the magnets at each station extends from the point 8 at one side of said station to the point 8 at the other side thereof, so that a train passing between these points will deenergize either 35 one of the magnets 9 and 10 of the station in that block according to which rail-section 5 the train is on, and the deenergizing of either of said magnets will break the supplemental circuit, hereinafter described, which 40 passes through the armatures and conductor-plate of said magnets.

At each station armature 13 is connected by a wire 21 to track-rail 6, and to one of the conducting elements of the companion armature 12 is connected a wire, as 22, which extends from this station to the second station beyond in one direction, while a second wire, as 23, extends to the second station in the other direction from the other conduct- 45 ing element of said armature 12; for instance, wire 22 from armature 12 of station C is led to station A while wire 23 from said armature is led to station E, and at these stations A and E each wire is con- 50 nected with a battery 24, which latter is

connected by wire 25 to track-rail 6. In the present instance there is located at the station and included in each supplemental circuit a short rail 27 and an electrically-operated signal or lamp 26. Each supplemental 70 circuit between any two stations therefore includes the following connections: between station A and station C, from battery 24 at station A to short-rail 27, to wire 22, to armature 12 at station C, through conductor- 75 plate 15 to armature 13, by wire 21 to track-rail 6, and through the latter back to battery 24 at said station A. The supplemental circuit between stations E and C includes exactly similar connections; and it will be 80 noted, therefore, that should either armature drop at station C both these circuits, to station A and to station E, would be broken. These supplemental circuits establish a signal condition whereby when a train occupies 85 any block a warning signal will be displayed to an approaching train at the second station in each direction from said block.

As the track-rails 5 and 6 form conductors 90 for both the working circuits which energize the electro-magnets and the supplemental circuits which operate the signals, the displacement of a rail of the track will establish a signal condition at the adjoining 95 stations; for instance the displacement of a rail of the track-rail 6 will break both the working and supplemental circuits passing at that point, while the displacement of a rail of any rail-section 5 will break the 100 working circuit passing through said rail-section.

The system as above described is applicable to single-track roads on which trains move in both directions, and on which it is 105 desirable to establish warning signal condition in both directions from the point of danger. It will be perfectly obvious, however, that my invention can, with slight modifications, be employed to equal advantage on double track roads where the traffic is in one direction only, and where, as a general thing, it is only necessary to provide 110 against rear end collisions.

While I have shown, for the sake of illustration, fixed signals 26 and batteries 24 located at each station, and while my system is admirably adapted for operating such way-side signals, it will be understood that the system is particularly designed for use in 120 connection with automatic signaling and train controlling devices located upon the train itself. Such devices include a contact shoe carried by the locomotive and adapted to engage the short rails 27 at each station, 125 and also include cab carried signaling and controlling circuits, and one or more batteries. In a copending application Serial No. 485,528, of even date herewith, I have shown and described such a cab signaling 130

and train controlling apparatus, designed for use in connection with the present system.

While I have used the word "battery" throughout the specification and claims, it will of course be understood that I mean to include primary or secondary batteries, generators, or other suitable sources of current. Having thus described my invention, what

10 I claim as new and desire to secure by Letters-Patent, is:—

15 1. In an automatic electric railway signaling system, the combination with a track divided into blocks, a signal station at each block junction point, a wire extending from each signal station to a station in advance and to a station in the rear, such wires co-operating with a rail of the track to form signal circuits, means for normally connecting said wires to each other and to the track rail, and means controlled by the presence of a train in a block adjacent the station for disconnecting said wires from each other and from the rail, thereby opening both signal circuits.

20 2. In an automatic electric railway signaling system, the combination with a track divided into blocks, a signal station at each block junction point, a relay connected to the rails at each end of each block, whereby there are two relays adjacent each station, one of said relays having a single armature, and the other of said relays having a pair of armatures electrically insulated but mechanically connected, a wire extending from said single armature to a rail of the track,

25 a second wire extending from one of the armatures of said pair to a signal station in advance, a third wire extending from the other of said armatures to a signal station in the rear, and a plate with which all three of said armatures are normally in engagement, whereby, when either relay is deenergized, and its armature falls away, the circuit to both signal stations is interrupted.

3. In an electric signal system for railways, a track divided into blocks, a signal station for each block, a relay connected to the rails of each block at each end thereof, whereby there are two relays adjacent each station, normally closed track circuits energizing said relays, one of said relays being provided with a pair of armatures electrically insulated but mechanically connected, and the other of said relays having a single armature, all of said armatures being normally magnetically suspended, a signal circuit extending from each station to a station on each side thereof, each of such circuits including one of said pair of armatures, respectively, and said single armature being included in both of said circuits, whereby, when either of said relays is deenergized, both said signal circuits are broken.

In testimony whereof I have signed my name to this specification in the presence of two subscribing witnesses.

HARRY J. WARTHEN.
